ILLUMINATING FLARE

Filed May 31, 1945

UNITED STATES PATENT OFFICE

2,448,471

ILLUMINATING FLARE

Conrad David Schermuly, Alfred James Schermuly, and Charles Schermuly, Parkgate, Newdigate, England

Application May 31, 1945, Serial No. 596,850
In Great Britain June 29, 1944

4 Claims. (Cl. 102—7)

1

This invention relates to illuminating flares and has for its object to provide means whereby a flare can be dropped from an aircraft into water and be ignited in the water.

According to this invention a flare device adapted to burn while floating on water comprises a casing, a buoyancy chamber on said casing, a flare candle within said casing, a removable cover enclosing the lower part of said casing, a fuze in said cover adapted to be ignited when the device strikes the water, a candle ignition train leading from a point adjacent said fuze to the top of said flare candle and adapted to be ignited by said fuze, a separating charge within said cover for the purpose of separating said cover from said casing and means for igniting said separating charge after the ignition of said candle ignition train.

The invention will now be described with reference to the accompanying drawing which is a sectional elevation of a flare device in accordance with the invention, but the invention is not limited to the particular device shown.

A casing 1 is provided with a buoyancy chamber 2. The lower part of the casing 1 is enclosed within a cover 3 which is secured to a swaged portion 4 of the buoyancy chamber 2 by a weak soft solder joint 5. The upper end of the casing 1 is closed by a cap 6 having a central orifice over which a cover plate 7 is secured by a weak soft solder joint. The upper end of the buoyancy chamber 2 is provided with stabilizing fins 8 to steady the device when it is dropped from an aircraft. The casing 1 contains a flare candle 9 which is held in position by means of a spacer 10. The top of the flare candle 9 is closed by a cover 11 of combustible material, such as book muslin, to which is secured a looped strip 12 of primed cambric. The lower end of the casing 1 carries a block 13 secured thereto. This block 13 has a central orifice 14 containing a charge of powder 15 and a passage 16 through which passes a length of instantaneous fuze 17. One end of the fuze 17 is embedded in the charge 15 and the other end is joined to a length of delay fuze 18. In contact with the upper end of the delay fuze 18 is a length of quickmatch 19 lightly stamped down at its lower end at 20. The quickmatch 19 is contained in a tube 21, for example of copper, which passes through the buoyancy chamber 2. The upper end of the quickmatch 19 is tied at 22 to another length of quickmatch 23 which is looped through the strip 12. The quickmatch 23 is surrounded by a paper tube 24.

The lower end of the cover 3 is closed by a

2

cap 25 having a central hole for the passage of a contact fuze 26. Between the cap 25 and the block 13 are arranged a metal block 27, a primed cambric disc 28 and spacers 29, all of these having a central aperture. The metal block 27 serves as a weight to ensure that the device assumes the correct position when dropped into water. The block 27 is provided with an annular recess which is filled with a separating charge 30, and with a small hole 31 through which passes a short length of quickmatch 32, one end of which is embedded in the separating charge 30 and the other end of which is in contact with the primed cambric disc 28. Another short length of quickmatch 33 connects the primed cambric disc 28 with the charge 15.

When the device is released from an aircraft, it falls with the contact fuze directed downwardly, the fall being stabilized by the fins 8. When the fuze 26 strikes the water it is actuated and the flash therefrom ignites in turn the charge 15, the instantaneous fuze 17, the delay fuze 18, the quickmatches 19 and 23, the strip 12, the cover 11 and the candle 9. The charge 15 also ignites in turn the quickmatch 33, the cambric disc 28, the quickmatch 32 and the separating charge 30. The explosion of the charge 30 causes the cover 3 to be separated from the buoyancy chamber 2 at the weak joint 5, and the cover 3, the block 27 and the spacers 29 fall away from the casing 1 which thereupon floats on the surface of the water by virtue of the buoyancy chamber 2. The ignition of the candle ignition train (15, 17, 18, 19, 23, 12, 11) is well started before the separation of the cover 3. The gases developed by the burning candle 9 force off the cover plate 7.

We claim:

1. A flare device adapted to burn while floating on water comprising a casing, a buoyancy chamber on said casing, a flare candle within said casing, a removable ballistic covering enclosing the lower part of said casing, a fuze in said cover adapted to be ignited when the device strikes the water, a candle ignition train leading from a point adjacent said fuze to the top of said flare candle and adapted to be ignited by said fuze, a separating charge within said cover for the purpose of separating said cover from said casing, said ignition train comprising a charge of powder adapted to be ignited by said fuze, an instantaneous fuze having one end embedded in said charge, a delay fuze joined at one end to said instantaneous fuze and a length of quickmatch joined at one end to said delay fuze and

at the other end to the top of said flare candle and powder train means between the fuze and separating charge whereby said separating charge is ignited after the ignition of said candle ignition train.

2. A flare device as claimed in claim 1 in which the cover is secured to a swaged portion of said buoyancy chamber by means of a weak soldered joint.

3. A flare device adapted to burn while floating on water comprising a casing, a buoyancy chamber on said casing, stabilizing fins on said buoyancy chamber, a flare candle within said casing, a removable cover enclosing the lower part of said casing, a weak joint securing said cover to said buoyancy chamber, a heavy plate having an annular recess in said cover, a fuze in said cover adapted to be ignited when the device strikes the water, a candle ignition train leading from a point adjacent said fuze to the top of said candle and adapted to be ignited by said fuze, said candle ignition train comprising a charge of powder adapted to be ignited by said fuze, an instantaneous fuze having one end embedded in said charge, a delay fuze joined at one end to said instantaneous fuze and a length of quick-match joined at one end to said delay fuze and

at the other end to the top of said flare candle, a tube extending from the bottom to the top of said buoyancy chamber for the reception of part of said candle ignition train, a separating charge in said recess for separating said cover from said casing and means for igniting said separating charge after ignition of said candle ignition train.

4. A flare device as in claim 3 wherein the weak joint is a soldered joint.
